UNITED STATES PATENT OFFICE.

MELACH J. NUSIM, OF EASTON, PENNSYLVANIA, ASSIGNOR TO INGERSOLL-RAND COMPANY, OF JERSEY CITY, NEW JERSEY, A CORPORATION OF NEW JERSEY.

IMPELLEEE.

Application filed March 31, 1921. Serial No. 457,241.

To all whom it may concern:

Be it known that I, MELACH J. NUSIM, a citizen of the United States, a resident of Easton, county of Northampton, and State 5 of Pennsylvania, have invented a certain Impeller, of which the following is a specification, accompanied by drawings.

This invention relates to impellers for single or double flow centrifugal blowers, 10 compressors and the like, but more particularly to impellers of the open type, adapted for axial intake and radial discharge, although my construction may be found applicable to impellers of the closed type.

15 The web of an impeller of the type to which this invention relates, is provided with blades having entrance edges suitable for receiving the air or other gas being handled, from an axial approach, imparting velocity 20 to the air or gas, and then discharging it radially at the peripheries or exit edges of the blades.

Heretofore the hub, web and blades of an impeller of the type referred to have been 25 built up in a number of separate sections or pieces and the blades themselves have usually been formed in sections, for instance, by making the intake portions of the blades separate from the discharge portions.

30 I have found that the impeller may be simplified and at the same time strengthened by constructing the entire impeller in one piece, that is, by making all parts, including the hub, the web and the blades out of one 35 piece of metal.

I have devised a method for making the entire impeller, whether single or double flow, out of one piece of metal, which includes certain milling and bending operations, to be described, in order to construct the blades in one piece, with the hub and web, but I am not to be understood as limiting the invention to any particular method, as other methods may be devised by those 45 skilled in the art for producing a similar structure having the advantages of my improved impeller.

One preferred form of impeller is shown in the accompanying drawings, in which 50 Figure 1 is a side elevation partly broken away of an impeller, with the shaft in transverse section, and a portion of the blades indicated to illustrate their shape.

Figure 2 is a transverse sectional elevation of the impeller on the line 2-2 of Fig-

ure 1 looking in the direction of the arrows.

Figure 3 is a top plan view of Figure 1, and

Figure 4 is a detail top plan view of one blade, and a portion of the hub and web of 60 the impeller illustrating the shape of the blades before and after bending the intake portions.

Referring to the drawings, the impeller is mounted on a suitable shaft A, and rotates 65 within a casing B, only a portion of which is shown. The impeller comprises a thickened hub portion C, a thinner circular web D, and blades E, carried by the hub and web and adapted for axial intake and radial discharge. The circular web D extends as usual, in a plane transversely to the longitudinal axis of the hub and preferably tapers gradually from the hub portion to the periphery F of the web, the hub and web preferably merging in a gradual curve as indicated particularly in Figure 2.

As indicated in accordance with my invention, the hub, web and blades constitute one integral structure formed from a single 80 piece of metal, but as finally formed, the impeller blades extend from the base of the thickened hub portion to the periphery of the web and are provided with sharply defined inner intake portions G bent transversely to the longitudinal axis of the hub while the outer radial portions H of the blades preferably terminate substantially at the periphery F of the web at which the exit edges J of the blades are located. 90

In constructing the impeller the blades may be milled out of the solid metal as indicated in full lines in Figure 4, so that the intake portions G project beyond the hub portion C in an axial direction. These intake portions G are then bent after milling by the application of localized heat until they assume substantially the positions indicated in dotted lines in Figure 4, in which they extend in a direction transverse to the 100 axis of the shaft or the axis of the impeller, and serve to draw in the air from an axial approach.

The blades are supported upon and carried by both the hub and web, since they are 105 integral with both of said portions of the impeller, and a stiff and strong impeller is produced having blades which present smooth unbroken driving faces to the air, without obstructions of any kind, which 110

increase the economy and efficiency of the impeller.

I claim:

1. An impeller for centrifugal blowers, compressors and the like, adapted for axial intake and radial discharge, and comprising a thickened hub portion having a thinner circular web extending transversely to the longitudinal axis of the hub, said web 5 tapering gradually from the hub portion to the periphery of the web, and blades extending from the base of the said thickened hub portion along the sides of the hub and web to the periphery of the web and provided with sharply defined inner intake portions lying in part directly upon the thickened hub portion and bent transversely to the longitudinal axis of the hub and projecting beyond the hub portion in an axial direction, the outer 10 portions of the blades extending radially, and the exit edges terminating substantially at the periphery of the said web, the said hub, web, and blades all being formed in one piece.
2. An impeller for centrifugal blowers, compressors and the like, adapted for axial 15

intake and radial discharge, and comprising a thickened hub portion having a thinner circular web extending transversely to the longitudinal axis of the hub, said web 30 tapering gradually from the hub portion to the periphery of the web, and blades extending from the base of the said thickened hub portion along the sides of the hub and web to the periphery of the web, and provided with sharply defined inner intake portions lying in part directly upon the thickened hub portion and bent transversely to the longitudinal axis of the hub and projecting beyond the hub portion in an axial direction, the outer 35 portions of the blades extending radially, and the exit edges terminating substantially at the periphery of the said web, the said hub, web, and blades all being formed in one 40 piece and the outer ends of said integral web and blades presenting a smooth and unobstructed driving face.

In testimony whereof I have signed this specification.

MELACH J. NUSIM.
